US00D649827S

(12) **United States Design Patent**
Smiedt et al.

(10) **Patent No.:** US D649,827 S
(45) **Date of Patent:** ** Dec. 6, 2011

(54) **PITCHER**

(75) Inventors: **Richard Smiedt**, New York, NY (US);
Karim Rashid, New York, NY (US)

(73) Assignee: **Move Collective LLC**, New York, NY
(US)

(**) Term: **14 Years**

(21) Appl. No.: **29/393,503**

(22) Filed: **Jun. 6, 2011**

Related U.S. Application Data

(62) Division of application No. 29/386,764, filed on Mar. 4, 2011.

(51) **LOC (9) Cl.** **07-01**

(52) **U.S. Cl.** **D7/319**; D7/316

(57) **CLAIM**

The ornamental design for the pitcher, as shown and described.

DESCRIPTION

FIG. 1 is an isometric view of a pitcher according to a first embodiment of the present design.

FIG. 2 is a top plan view of the first embodiment.

FIG. 3 is a bottom view of the first embodiment.

FIG. 4 is a front view of the first embodiment.

FIG. 5 is a right side view of the first embodiment.

FIG. 6 is a left side view of the first embodiment.

FIG. 7 is an isometric view of a second embodiment of the present design.

FIG. 8 is a top plan view of the second embodiment.

FIG. 9 is a bottom view of the second embodiment.

FIG. 10 is a front view of the second embodiment.

FIG. 11 is a right side view of the second embodiment; and, FIG. 12 is a left side view of the second embodiment.

The broken line showings are for illustrative purposes only and form no part of the claimed design.

1 Claim, 10 Drawing Sheets
